CLAIM

The ornamental design for display screen or portion thereof with graphical user interface, as shown and described.

DESCRIPTION

The single FIGURE is a front view of a display screen or portion thereof with graphical user interface showing our new design.

The outermost dash-dot broken lines in the drawings illustrate the display screen or portion thereof and form no part of the claimed design. The dotted broken lines in the drawings illustrate portions of the graphical user interface that form no part of the claimed design.

1 Claim, 1 Drawing Sheet
